UNITED STATES PATENT OFFICE.

GEORGE S. LEWIS AND ALBERT G. LAMPORT, OF SYRACUSE, NEW YORK,
ASSIGNORS TO THE LE FEVER ARMS COMPANY, OF SAME PLACE.

BREECH-LOADING FIRE-ARM.

SPECIFICATION forming part of Letters Patent No. 371,605, dated October 18, 1887.

Application filed January 24, 1887. Serial No. 225,405. (No model.)

To all whom it may concern:

Be it known that we, GEORGE S. LEWIS and ALBERT G. LAMPORT, of Syracuse, in the county of Onondaga, in the State of New York, 5 have invented new and useful Improvements in Breech-Loading Fire-Arms, of which the following, taken in connection with the accompanying drawings, is a full, clear, and exact description.

10 Our invention relates to improvements in the class of breech-loading fire-arms using so-called "concealed hammers," in which the hammers are incased in the shell of the breech out of sight; and the object of the invention 15 is to provide means for connecting the top lever, which throws or releases the locking-bolt from the top fastener by suitable means, whereby the top lever swings back to its normal position immediately when released after breaking 20 the arm, and remains at rest when the barrels are closed and locked to the breech, and also to so construct the means for throwing up the hammers as the arm is broken as to compel the push rod or lever used for this purpose to 25 clear the hammer when the barrels are closed, thus relieving the hammer from throwing back the push-lever and overcoming the tendency of the arm to miss fire, which frequently occurs now when the parts get gummed up so as to 30 work with difficulty; and to this end our invention consists in providing a locking-bolt with a pin projecting upward from a slot in the tang, and providing the top lever with a recess coincident with the slot in the tang 35 when the lever is in its normal position, into which the pin projects against the forward shoulder of the recess, whereby the bolt is allowed a free rearward movement without moving the top lever when the top lever is at rest, as 40 more particularly described hereinafter; and it furthermore consists in connecting the push-lever for cocking the hammers to the actuating-eccentric by means of a link or toggle, whereby the push-lever is withdrawn from its 45 contact with the hammer after having cocked the hammer when the barrels are closed and locked to the breech, all as more fully hereinafter described, and pointed out in the claims.

In specifying our invention reference is had 50 to the accompanying drawings, in which, like

letters indicating corresponding parts, Figure 1 is a side elevation, partly in section and with the side plate broken away, for the purpose of illustrating our invention applied to the breech-loading fire-arm. Fig. 2 is a top 55 plan with the top lever removed, showing the slot in the tang and the pin extending upward from the locking-bolt lying in the slot. Fig. 3 shows an enlarged detached detail of the push-lever and eccentric for cocking the 60 hammers; and Fig. 4 shows an inverted plan of the top lever provided with a recess which, when the top lever is applied in position, as shown in Fig. 1, is coincident with the slot in the tang. 65

A represents the breech of a breech-loading fire-arm, and B the barrels, pivoted to the breech in the usual manner, the breech A being provided with a recess, F, for the top fastener, E, secured to the barrels, to engage with, 70 and also with the locking-bolt a, provided with the nose m, which takes in the notch i in the top fastener, E, when the barrels are closed, and the said bolt a forms the main locking-bolt of the action and serves to lock the barrels B securely to the breech A. 75

D is the top lever, constructed in the usual manner, with the exception presently explained.

The parts thus far described are constructed 80 in the form and manner of the so-called "concealed-hammer" guns, which are well known to those skilled in the art, and the action of this class of guns is what is usually termed "top-lever" or "snap" action. In this form of action (while in many respects it has been the most desirable, for the reason that the arm is readily broken by simply swinging the top lever to one side on its pivot, which is easily accomplished, since the top lever is pivoted 85 so as to secure considerable leverage) there has been a serious objection, for the reason that in the ordinary construction the top lever was actuated by both the opening and closing of the barrels, causing great strain on its 90 pivot and vibration, making the action hard and soon worn out; and the chief object of our present invention is to so connect the top lever to the locking-bolt as to prevent one movement of the top lever in the operation of open- 95 100

ing and closing the barrels, thus reducing the wear and strain on the parts one-half at least, and thereby greatly increasing the durability and ease of movement of the action; and this 5 desirable result we secure by providing the stud-pin *b*, Fig. 1, secured to the top of the locking-bolt *a*, and slotting the tang *T* at *c*, as best shown in Figs. 1 and 2, and providing the top lever, *D*, with the recess *n*, Fig. 4, the 10 said recess *n* being coincident with the slot *c* when the top lever, *D*, is in its normal position, and the pin *b* extends up into the recess *n*, engaging with the forward end or shoulder, *n'*, of the said recess.

15 It will be observed that when the top lever, *D*, is swung off on its pivot *o* the shoulder or forward end, *n'*, of the recess in the top lever retracts the pin *b*, carrying the locking-bolt *a* with it, thus releasing the nose *m* of the bolt 20 from the notch *i* in the top fastener, *E*, and allowing the barrels *B* to tilt on the hinge pin or pivot, thereby breaking the arm. When the top lever is released, it is immediately returned to its normal position by the spring of 25 the action, and the slot *c* and recess *n* permit the locking-bolt to be retracted by the contact of the curved portion *l* of the top fastener colliding with the curved nose *l'* of the locking-bolt when the barrels are closed without moving 30 the top lever, *D*, thus securing the desired result.

The hammers *d* are cocked when the arm is broken by means of the push-lever *e* pushing against the shoulder *c'* of the hammer *d* by 35 the eccentric *g*, pivoted at the forward end of the recess so as to swing backward as the strap *C*, having the recess *h*, collides with the rectangular end of the eccentric *g*, and, as heretofore constructed, the rod *e* was detached from the eccentric *g*, and was forced 40 back to its normal position by the forward movement of the hammer *d* when the arm was discharged, and when the arm was used for a while the parts were liable to become 45 gummed and sticky, and the force required to push forward the lever *e* frequently caused arms of this class to miss fire; and to overcome this defect and to secure a greater leverage on the rod *e* we secure the push lever or 50 rod *e* to the eccentric *g* by means of the link or toggle connection *f*, as best shown in Figs. 1 and 3, and construct the recess *h* in the fore-end strap *C* of the form shown in Fig. 1, and this construction secures the desired result, 55 for the reason that when the arm is broken and the barrels tilted upward the movement of the strap *C* forces down or causes the eccentric *g* to swing on its pivot *g'*, and the link or toggle *f* transmits the motion and force to the 60 rod *e*, and the rod *e* forces the hammer *d* to a full-cock with great ease and freedom of movement, while the link *f*, connecting the rod *e* to the eccentric *g*, serves a double office by retracting the rod or push-lever *e* automatically 65 as the barrels are closed after the arm has been opened for the purpose of inserting the charge.

The operation of our invention will be readily understood from the foregoing and a consideration of the drawings.

When it is desired to charge the arm, the top lever, *D*, is swung off, and such movement withdraws the locking-bolt *a* from its engagement with the notch in the top fastener, and the arm then opens as the barrels tilt upward. 75 The fore-end strap *C* causes the eccentric *g* to turn on its pivot *g'*, and this movement pushes the lever or push-rod *e* backward, cocking the hammers *d*, and after the charge is inserted the barrels are locked by pressing them 80 down into place in the breech, and in this movement the top lever remains at rest in its normal position, while the push-lever *e* is retracted to its normal position by means of the link or toggle connection *f*. The construction 85 is simple, compact, and durable, and affords very effective means for the purpose intended.

Having thus fully described our invention, what we claim as new, and desire to secure by Letters Patent, is—

90 1. In a breech-loading fire-arm, the combination of the locking-bolt provided with a pin projecting upward from the bolt into a slot in the tang, and the top lever provided with a recess coincident with the slot in the tang 95 when the lever is in its normal position, the forward shoulder of the recess engaging with the pin to release the locking-bolt from the top fastener when the lever is swung from its normal position in breaking the arm, substantially as and for the purpose set forth.

2. The combination of the locking-bolt *a*, pivoted in the breech *A*, and provided with the pin *b*, projecting through slot *c* in the tang of the breech, with the top lever, *D*, having 105 an elongated recess, substantially as and for the purpose set forth.

3. The combination of the hammer *d*, push-rod *e*, and eccentric *g*, located at the forward end of the breech-extension, having the rod *e* 110 connected thereto by a link, *f*, and the strap *C*, substantially as and for the purpose set forth.

4. The combination, in a fire-arm, of a locking-bolt and top lever connected together by 115 an upwardly-projecting pin secured to the locking-bolt and an elongated recess in the top lever, whereby the bolt and top lever co-operate in breaking the arm and act independently of each other in closing the same, 120 substantially as and for the purpose set forth.

In testimony whereof we have hereunto signed our names, in the presence of two attesting witnesses, at Syracuse, in the county of Onondaga, in the State of New York, this 19th 125 day of January, 1887.

GEORGE S. LEWIS.
ALBERT G. LAMPORT.
